(57) **CLAIM**

The ornamental design for a “satellite locator,” as shown and described.

DESCRIPTION

FIG. 1 is a perspective view of a “satellite locator” showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view of the present invention; and,

FIG. 9 is a perspective view of the present invention, showing an antennal module thereof being in a closed position.

1 Claim, 6 Drawing Sheets
